PHOTOGRAPHIC CAMERA OR SIMILAR ARTICLE

Richard J. Olson, Pittsford, N.Y., assignor to Eastman Kodak Company, Rochester, N.Y., a corporation of New Jersey

Filed Mar. 29, 1968, Ser. No. 11,193

Term of patent 14 years

Int. Cl. D16—01

U.S. Cl. D61—1

FIG.1

FIG.2

FIG. 3

FIG. 4

FIG. 1 is a front perspective view, taken from the upper-right corner, of a photographic camera or similar article, showing a first embodiment of my new design wherein an operating member protrudes from a rear portion of the camera or similar article;

FIG. 2 is a rear perspective view, taken from the lower-left corner, of the embodiment shown in FIG. 1;

FIG. 3 is a front perspective view, taken from the upper-right corner, of a photographic camera or similar article, showing a second embodiment of my novel design wherein an operating member protrudes from a top portion of the camera or similar article; and

FIG. 4 is a rear perspective view, taken from the lower-left corner, of the embodiment shown in FIG. 3.

I claim:

The ornamental design for a photographic camera or similar article, as shown and described.
